PAPER CARRIAGE DRIVE

Oscar J. Sundstrand, Rockford, Ill., assignor, by
mesne assignments, to Underwood Elliott
Fisher Company, New York, N. Y., a corpora-
tion of Delaware

Application October 13, 1930, Serial No. 488,293

6 Claims. (Cl. 197—65)

This invention relates to printing machines such as typewriters, adding machines and the like, and has particular reference to a machine of this class having a cross-tabulating carriage.

5 The object of the invention is to provide simple and effective means whereby the carriage may be driven in its working stroke and its return stroke by a single motor.

In the accompanying drawing:

10 Figure 1 is a fragmental left-hand side elevation of a bookkeeping machine comprising a cross-tabulating carriage arranged to be driven by means embodying the features of my invention.

15 Fig. 2 is a fragmental sectional view of the means for imparting the return stroke to the carriage.

Fig. 3 is a fragmental rear elevation of the machine.

The paper carriage 1 may be of any preferred 20 construction and may be supported for movement transversely of the machine frame in any desired manner, as, for example, upon a guide 2 and anti-friction rollers 3. In its cross-tabulating or working stroke the carriage travels toward the left 25 of the operator, toward the observer in Fig. 1 and to the right in the rear view shown in Fig. 3. It is moved in this direction by means including a flexible element such as the draw band 4, the latter being secured at one end to the carriage 30 and running over a drum or guide pulley 5 and thence around a pulley 6 to which it is secured at a suitable point, as, for example, the point 7 in Fig. 3. The drum 5 is rotatably mounted in the stationary framework of the machine below and 35 close to the path of travel of the carriage. The pulley 6 is journaled upon a fixed shaft 8 directly below the drum 5, and is rigidly connected to an internal gear 9 of substantially equivalent diameter. Meshing with said gear is a pinion 10 fixed 40 upon a shaft 11, the gear and pinion constituting in this embodiment of the invention, a preferred form of speed reduction gear train. The shaft 11 is driven from an electric motor 12 in any preferred manner which permits of slippage or lost motion. Herein I have shown a pulley 13 fixed 45 upon the rear end of the motor shaft 14 and carrying a belt 15 that runs over a pulley 16. The pulley 16 is rotatably mounted upon the shaft 11 and is connected thereto by means of a friction clutch 17. While this clutch may be of any desired character, it is herein shown as comprising a plurality of friction disks, certain of which are connected to rotate with the pulley 16 by means 50 of pins 18, said disks alternating with other disks

which are splined to the shaft 11. The disks are yieldingly pressed together by means of a spring 19. By reference to the arrow in Fig. 3, it will be seen that the drive just described operates to drive the carriage in the working direction. The 5 motor 12 operates continuously, except that, if desired, the motor circuit may be arranged to be opened after the lapse of a certain length of time after an operation of the machine.

The means for returning the carriage to its 10 initial position may be of any desired character. Herein I have shown a gear train indicated generally at 20 through which power is transmitted from the forward end of the motor shaft 14 to a vertical shaft 21. Rotatably mounted upon the 15 upper end of the shaft 21 is a pinion 22 that meshes with a rack 23 which is fixed to and extends longitudinally of the paper carriage 1. The pinion 22 is arranged to be connected to rotate with the shaft 21 by means of a clutch collar 24 20 adapted to engage a clutch face 25 on the pinion 22. The clutch collar 24 is slidably and non-rotatably connected to the shaft 21 by means of a spline 26 (Fig. 2). Means of any ordinary or preferred character may be provided for shifting 25 the clutch collar 24 into and out of engagement with the pinion 22 either automatically or manually, or both, at any desired point in the cross-tabulating movement of the carriage.

It will be seen that when the clutch collar 24 30 is shifted into engagement with the pinion 22 the latter will be driven in the direction to return the paper carriage 1 to or toward its initial position. Since the gear drive 20 acts positively to drive 35 the paper carriage, it overcomes the friction drive which tends at all times to drive the carriage in the working direction, the clutch 17 slipping while the clutch collar 24 is in engagement with the pinion 22.

An escapement mechanism of any well-known 40 or preferred construction may be provided to control the movement of the carriage in the working stroke. Herein I have shown tabulating stops 27 mounted on the carriage 1 and coating with a 45 stop element 28 suitably mounted upon the stationary framework of the machine. It will be understood that while the carriage is held stationary through the engagement of one of the tabulating stops 27 with the stop element 28, the 50 clutch 17 slips as the motor continues to operate.

It will be seen that I have provided a simple and effective mechanism whereby a single motor may be caused to cross-tabulate the carriage as well as return it to initial position.

Obviously the power train composed of the elements 13, 16, 10, 9, 6 and 5 effects a great reduction in speed from that of the motor.

I claim as my invention:

- 5 1. In a printing machine, the combination of a laterally movable paper carriage, a motor, a constantly acting impositive driving connection between the motor and the carriage for moving the latter in the working direction, and a normally inoperative positive driving connection between the motor and the carriage for returning the carriage toward its initial position.
- 10 2. In a printing machine, the combination of a laterally movable paper carriage, a motor, a constantly acting impositive driving connection between the motor and the carriage for moving the latter in one direction, and a positive driving connection between the motor and the carriage for moving the carriage in the opposite direction, said positive connection comprising a power-transmitting member movable into and out of effective position.
- 15 3. In a printing machine, a laterally movable paper carriage, a flexible member connected to the carriage, a guide pulley over which said flexible element is arranged to extend, a pulley around which said flexible element is wound after passing over said guide pulley, an electric motor, a driving connection between the motor and the second pulley effective to propel said carriage in working direction, said driving connection including a friction clutch operating at substantially the speed of said motor, a speed reduction gear train between said clutch and said second mentioned pulley, and a normally

inoperative connection between said motor and said carriage to drive said carriage in a return direction.

4. In a printing machine, a laterally movable paper carriage, an electric motor, a permanently connected impositive speed-reducing train for transmitting movement from the motor to the carriage to drive the latter in one direction and a positive driving connection between the motor and the carriage for moving the latter in the opposite direction, said positive connection containing a power-transmitting member movable into and out of effective position. 5

5. In a printing machine, a laterally movable paper carriage, a driving motor, a permanently operative impositive driving connection between the motor and carriage effective to move the latter in one direction and a normally inoperative positive driving connection between the motor and the carriage for moving the latter in a reverse direction against the action of said impositive connection. 10

6. In a printing machine, the combination of a laterally movable carriage, a motor, a permanently enabled impositive driving connection between the motor and the carriage for moving the latter in one direction, a normally disabled positive driving connection between said motor and carriage, and a part operable to enable said positive connection to move said carriage reversely to said first mentioned direction against the action of said impositive connection. 20 25 30

OSCAR J. SUNDSTRAND.
